UNITED STATES PATENT OFFICE.

AUGUST G. SANDMAN, OF ST. DENIS, MARYLAND.

COMBINED AIR AND HAND BRAKE.

SPECIFICATION forming part of Letters Patent No. 769,359, dated September 6, 1904.

Application filed April 1, 1896. Renewed February 13, 1904. Serial No. 193,469. (No model.)

To all whom it may concern:

Be it known that I, AUGUST G. SANDMAN, of St. Denis, Baltimore county, State of Maryland, have invented certain new and useful 5 Improvements in a Combined Air and Hand Brake, of which the following, taken in connection with the accompanying drawings, is a specification sufficiently full, clear, and accurate as will enable car-builders to make, apply, 10 and use the same.

The objects of my invention are the production of a hand-brake and an air-brake each of which may be used independently of the other and the hand-brake adapted to reinforce 15 the air-brake and also to hold the shoes against the wheels should air leak from the cylinder and the piston travel to a released or partly-released position.

With these objects in view the invention 20 consists in so constructing and arranging various parts of the rigging that certain parts of it may be moved relative to other parts thereof without imparting motion to the latter.

Still further, it consists in adapting the combined apparatus for use on a hopper-bottom car.

Figure 1 illustrates in dotted lines a plan view of a hopper-bottom car and in full lines the air and hand brake apparatus in operative 30 position. Fig. 2 is a side view of Fig. 1 with the air-brake cylinder removed and also showing in dotted lines the downwardly-projecting hoppers on each side of the longitudinal stringers. Fig. 3 is a cross-section of Fig. 1, 35 taken on a line between the brake-cylinder and the body-bolster and through the longitudinal stringers and brake-connecting rods; and Fig. 4, a detail view of a flexible connection between the connecting-rod and a non-floating 40 lever.

As is well known to those skilled in the art, many hopper-bottom cars are constructed by locating two or more longitudinal stringers on the line of buffing and towing and two side 45 sills at equal distances from the central stringers. The downwardly-projecting hoppers occupy the area between the central stringers and side sills. This arrangement leaves an open space directly under the stringers for the 50 passage of the air-brake pipe, brake-rods, &c.

My improvements are adapted for use on a car constructed substantially as thus described.

A is an air-brake cylinder. B B are brake-cylinder levers. C is a brake-cylinder-lever tie-rod. D and D' are connecting-rods; E and 55 E', non-floating levers each pivoted at one end in brackets F F'; G G', upper brake-lever-connecting rods. These elements constitute necessary parts of the air-brake system.

P is a hand-brake-connecting rod attached 60 at one end to the ordinary chain and perpendicular hand-brake staff and at the other to a bent floating lever R. One end of this lever R is flexibly united in any convenient way to the lever E or rod G. A rod T also connects 65 the lever R with one of the levers B or with the rod D'. If preferred, this rod T, as shown in dotted lines, may extend between the floating lever R and the non-floating lever E'.

To allow the hand-brake and air-brake to 70 be operated each independently of the other, certain yielding or flexible elements must be introduced at convenient points between the two. I therefore show, by way of example, a flexible connection between the end of lever 75 R and lever E or rod G and also a sliding connection between rod D' and lever E. However, in place of the latter I may substitute a yielding or sliding connection at any other convenient point—as, for illustration, between 80 the cylinder-levers and the cylinder-lever tie-rod or between the end of the rod D and the cylinder-lever B. Should the rod T extend the entire distance between the lever R and the lever E', the flexible element may be otherwise disposed. I have shown a chain S 85 uniting lever R and lever E or rod G; but should a rigid element take the place of the chain S the yielding or sliding element might be located at the point of connection of lever 90 R with rod T or otherwise located. I have shown in Fig. 4 the rod D bifurcated at the end and having a slot I, within which travels the pivot-pin H of the lever E; but any other suitable yielding or sliding connection may 95 be substituted.

It is to be noted that the arrangement of the rigging is especially adapted to the construction of a hopper-bottom car. The brake-cylinder occupies the open space between the 100

hopper. The rods are located beneath the central stringers in the longitudinal unobstructed space adjacent thereto and the lever R bent so that the rod T may occupy a position under 5 the rod D or D and D'.

The mode of operation is as follows: When the engineer shifts his lever and air is allowed to escape from the train brake-pipe, air is admitted to the cylinder, the piston moved, the cylinder-levers rotated, the rods D and D' advanced, and the shoes brought in contact with the wheels. The free movement of these various elements is not restricted or interfered with in any way by the hand-brake device by 10 reason of the presence of the flexible or yielding element S, for it permits the lever E to be advanced toward the left and the rods D' and T and the lever R to move toward the right. After the air-brake has been fully 15 applied it may be reinforced by the hand-brake transmitting energy through the chain S and rod T to the air-brake rigging. It is also obvious by reference to the flexible or yielding connection between the lever E and 20 the rod D or to a yielding connection at some other suitable point that the hand-brake may be applied independently of the air-brake, for as the lever R is rotated and imparts motion to the lever E the pivot H can move in the 25 slot I and not disturb the other parts of the 30 air-brake rigging.

While I have shown, by way of example, only one specific application and in dotted lines one modification of my invention and in 35 the description referred to several possible specific variations or modifications, I do not consider any one or all of them as exhaustive of my invention. Changes can be made and elements substituted, and each and all I shall

consider as equivalents of my specific devices 40 when the change made or elements substituted preserves the function or functions of operation to secure the end or ends which constitute the purposes and objects of my invention. 45

What I claim as new, and desire to secure by Letters Patent, is as follows:

1. A combined air-brake and hand-brake mechanism embracing as constituent elements non-floating levers, supports on the car-body, 50 upper brake-lever-connecting rods, the hand-brake-connecting rod, a lever R, element S, rod T, connecting-rods D, D', tie-rod C, cylinder-levers B, B, and an air-cylinder and piston; in substance as set forth. 55

2. The combination with air-brake rigging of hand-brake rigging embracing as main elements a rod T, lever R, flexible element S for transmitting motion to rod G, and a suitable yielding connection between the air-brake 60 rigging and the hand-brake rigging; in substance as set forth.

3. The combination of a pair of non-floating levers, means for connecting them to the brakes, a pneumatically-actuated system of 65 levers connected to one of said non-floating levers by a yielding joint, a floating lever, a rod connecting its fulcrum to a member of the pneumatically-operated lever system, said floating lever having connections at one end 70 to a hand-wheel and at its other end by a flexible connection to the non-floating lever or connecting-rod.

AUGUST G. SANDMAN.
